UNITED STATES PATENT OFFICE

164,818

ELECTRONIC INSECT KILLER

James W. Ragsdale, St. Joseph Mo., assignor to
Acme Products Corporation, St. Joseph, Mo.,
a corporation of Missouri

Application April 2, 1951, Serial No. 14,684

Term of patent 7 years

(Cl. D31—3)

To all whom it may concern:

Be it known that I, James W. Ragsdale, a citizen of the United States, residing at St. Joseph, in the county of Buchanan and State of Missouri, have invented a new, original, and ornamental Design for an Electronic Insect Killer, of which the following is a specification, reference being had to the accompanying drawing, forming a part thereof, wherein:

Fig. 1 is a perspective view of an electronic insect killer, showing my new design; and

Fig. 2 is a bottom plan view thereof.

I claim:

The ornamental design for an electronic insect killer, as shown.

JAMES W. RAGSDALE.
